DOLL OR DISPLAY FIGURE

Mildred C. Wood, Langhorne, Pa.

Application October 18, 1939, Serial No. 299,939

12 Claims. (Cl. 46—162)

This invention relates to dolls, manikin display and lay figures, and, more particularly, to such figures having a reinforced foundation substantially encased in suitable wrapping to build up and give appropriate body contour to the desired figure.

The primary object of this invention is to provide a doll, manikin display and lay figure including a novel form of reinforced foundation whereby the device can be variously flexed and positioned in distinctive poses; for example, when the invention is embodied in a doll, the arms, legs and body portion, as well as the head, are movable into selected positions simulative of walking, sitting, dancing, running, and so forth.

Another object is to provide a doll, manikin, or lay figure, the various components of which can be relatively disposed for esthetic and effective display purposes with pre-assurance of normally holding the requisite pose.

A further object is to provide a device of the above indicated type that is simple to construct, durable in character, and which may be economically manufactured.

Other objects and ancillary advantages of this invention will appear from the following description considered in connection with the accompanying drawings, while the concluding claims more particularly express the features of novelty.

In the drawings:

Fig. 1 is a perspective view of a toy doll embodying a preferred form of this invention.

Fig. 2 is a face view of the reinforced foundation included in the doll of Fig. 1.

Fig. 2a is a section on the plane IIa—IIa of Fig. 2.

Fig. 3 is a rear view of Fig. 2.

Fig. 4 is a front elevation of the foundation shown by Figs. 2 and 3, in part encased with suitable strip material to the desired formative extent, and with other parts variously exposed to better illustrate underlying features.

Fig. 5 is a broken vertical section on the plane V—V of Figs. 2, 3 and 4, as viewed in the direction of the respectively associated arrows, said section being drawn to substantially larger scale for the better illustration of structural details.

Fig. 6 is a side elevation of the head portion of the doll as viewed in the direction of the arrows VI—VI in Fig. 4.

Fig. 7 is an enlarged top plan view of the head of the doll, before application thereto of the hair; or, as viewed in the direction of the arrows VII—VII in Fig. 4.

Fig. 8 is a cross-section taken on the plane VIII—VIII of Fig. 4, and drawn to a larger scale for clearer illustration.

Fig. 9 is a longitudinal section through the body and hips of the doll, or approximately on the plane IX—IX of Fig. 2, but drawn to a larger scale for better illustration of the details.

Fig. 10 is a vertical section through the leg lower portion and foot of the doll, taken approximately on the plane X—X of Fig. 2.

Fig. 11 is a perspective view of a body component of the doll hereinafter more particularly described.

Fig. 12 is a fragmentary plan view of a modified form of the reinforced foundation; and,

Fig. 13 is a section on the plane XIII—XIII of the preceding illustration.

In the following detailed disclosure of this invention, specific terms will be employed for the sake of clearness in description, and it is to be understood such terms are not limitative, but are intended to include all reasonable equivalents that may have analogous meaning.

Referring more in detail to the drawings, which, by way of example, illustrate a doll comprehensively designated in Fig. 1 by the reference 14, the same embodies a skeleton frame or foundation element 15, Figs. 2 and 3 more particularly. This foundation element 15, preferably severed from buckram or other suitable stiffening material, comprises a body section 16 with a neck and head 17, 18, respectively, integral therewith; whereas the leg and arm portions 19, 20 are of like material and relatively detached.

Secured to one face of the foundation 15 as by 35 stitching 21, is a reinforcement, preferably in the form of sinuous wire 22, said wire being medially expanded and bent along corresponding lines towards one another to provide a cross-brace 23 for the crown of the doll's head 18, with the adjoining sinuous sections 24 affording side support for the doll's face. In the lower portion of the head 18 the sinuous sections 24 are inwardly contracted or reduced, as shown at 25, to fit the neck 17, and then outwardly displaced to form 40 opposing bends 26 for the reinforcing of the shoulders 27 of the foundation 15. From the shoulder bends 26 extend sinuous body sections 28, conveniently made of greater width so as to transversely brace the buckram body part 16 45 substantially from its sides to proximate the center.

It will be observed the body section 16 is transversely slit inwards of the waist line 29, or from the side edges towards the center, but that 50 55

said slits do not extend wholly across the body section 16, so as to provide an intervening unsevered width 30, for a purpose later on again referred to. From the body sections 28 the sinuous wire is applied to the face of the buckram centrally down the legs 19 to proximate the toe portions 31, as clearly shown in, and understandable from, Figs. 2 and 10, more particularly; while all the sinuous and bend portions of 10 the wire 22, are continuously sewn to the adjoining parts of said foundation 15, in an obvious manner. Thus it will be seen that the front face of the buckram foundation 15 is effectively reinforced from the head 18 to the toe pieces 31, 15 while said foundation with the legs 19 are covered at the back with correspondingly contoured sheet sections 32, 33 of suitable material, such as felt.

To the back of the body section 16, with its 20 felt covering 32, there is stitched an additional sinuous wire reinforcement 34, the medial portion whereof embodies vertically directed elongated bends 35 which do not project below the waist line 29; whereas the continuing portions 36 25 of said reinforcement extend lengthwise of the arms 20 and are secured thereto by stitching 21, as before set forth. It is to be noted the reinforcement portions 36 are first threaded through holes 37 in the buckram and felt 38, 39, Fig. 2a, 30 of the arms 20 before being secured to the latter by the stitching 21; while the free ends of said portions 36 are appropriately turned at 40 to stiffen and shape the hands 41. In addition, the hands 41 and fingers 42 are reinforced at the 35 front by correspondingly contoured sinuous wires 43, sewn thereto as above described.

At the back, the legs 19 are further strengthened preferably by a length of sinuous wire 44 having the medial portion appropriately shaped 40 at 45 to conform with the lower portion of the body 16, or crotch of the doll 14, with the continuing sinuous parts of said wire extended down the legs 19 to some distance above the feet 46. The feet 46 are appropriately molded from suitable hard-setting composition with the lower ends of sinuous wire sections 47 embedded therein, while said sections 47 extend upwards and 45 partially overlap the lower sinuous parts 44 aforesaid, with the overlaps secured in place as by stitching 21 to provide for easy movement of the feet relative to the lower leg portions of the doll 14.

The arms 20 are additionally reinforced at the front by sinuous wire 48 appropriately included 50 as continuous lengths throughout the hands 41 and fingers 42, as clearly shown in Fig. 2.

After the foundation 15 is made up, as above set forth, a suitably contoured facing continuous length of felt or the like 49 is applied over the 55 head, body and legs 18, 16 and 19, respectively, with the surrounding edges attached as by stitching 50 to back feltings 32, 33.

The head 51 of the doll 14 is preferably made from molded composition, like the feet 46, in 60 front and back halves 52, 53, respectively; each said half having the ends of a longitudinally directed flexible strip 54 embedded therein, so that when the halves are placed in registration they can be secured together by one or more 65 lateral anchoring bands 55, Figs. 4 and 5-7; whereupon said halves 52, 53 are secured together by adhesive strips 56 in an obvious manner. The front half 52 of the head is provided with indentations 57, 58 and a protuberance 59, as foundations 70 for the eyes, mouth and nose, respectively.

When the foundation 15 and head 51 are made up, as above described, the body is wrapped with continuous strip material 60 with interposed padding of cotton-wool 61, for example, to give the desired rotundity to the body, legs and arms, 5 in accordance with known practice; whereupon hair 62 is applied to the head 51, and the doll appropriately dressed as illustratively depicted in Fig. 1.

Instead of the stitching 21, above described, 10 staples 63 such as shown in Figs. 12 and 13, may be clinched through the several components of the foundation 15; while said foundation 15 is preferably fitted with a protective device in the region of the waist line 29 in the form of a discous element 64, Fig. 11, of appropriate flexible sheet material to permit easy lateral flexing of the doll body. This element 64 has a suitable cut-out 65 defining segments 66 for passage through the waist line slits 29, and convenient 20 disposition of the segments 66 at the back of the foundation 15, as best shown in Fig. 3, while the edge 67 of said cut-out contacts the unsevered part 30 of said foundation, so that the severed parts may easily ride over one another, in an ob- 25 vious manner.

It is to be noted that the sinuous wire employed may be either of single strand type, or of multiple strands such as picture-wire, and of different gage in accordance with the required degree 30 of flexibility desired in the doll or lay figure. Similarly the material for building-up, backing, padding and wrapping, of the figure foundation may be of differing character to those specified without departing from the fundamental features 35 of the invention.

Having thus described my invention, I claim:

1. A foundation for dolls, manikins and lay figures, made from desirably contoured sheet material to include a head and body component 40 with relatively detached limb elements; a continuous basic reinforcement of sinuous wire medially bent to define complementary sections extending from the upper part of the head lengthwise of the body component and limbs; and 45 means for securing the sinuous reinforcement to one face of the foundation.

2. A foundation of the type defined by claim 1, wherein the sheet material is buckram or the like, the medial portion of the sinuous wire reinforcement is deformed to provide a crown brace 50 for the head, and said reinforcement affords movable connection for the limbs.

3. A foundation of the type defined by claim 1, further characterized by an additional reinforcement of sinuous wire applied to the reverse face of the body component with extension along an associated pair of the limbs, and said reinforcement includes a medial section of substantially longer bends for disposal in crosswise relation 60 to the basic reinforcement confronting bends.

4. A foundation for dolls, manikins and lay figures made from desirably contoured sheet material to include a combined head and body component, and plural pairs of relatively detached 65 limbs; a continuous basic reinforcement of sinuous wire medially bent to define complementary sections, said reinforcement being adapted to fit within the confines of the foundation head and body component with extension lengthwise 70 of one pair of the limbs; an additional reinforcement of like wire with medial portion embodying bends of greater extent than the flanking lengths, and said bends disposed crosswise relative to the body section portions of the basic reinforcement 75

with the flanking portions arranged lengthwise of the other pair of limbs and affording pivotal connection for the latter; and means for securing said sinuous reinforcements to the head and body component and the limbs.

5. A foundation of the type defined in claim 4, further characterized by an auxiliary sinuous wire reinforcement applied to the back of one pair of the relatively detached limbs, said auxiliary reinforcement having the medial portion deformed to fit the crotch of the body component intervening the associated pair of limbs, and individual lengths of similar reinforcing wire applied lengthwise of the other pair of limbs.

10 6. A foundation of the type defined in claim 4, further characterized by conformatory covering sheets of felt, and means securing said sheets to the foundation, in combination with strip material continuously wound about the covered foundation and intervening filler material to give the desired shape to the doll, manikin, or lay figure.

15 7. A foundation for dolls, manikins, and lay figures as defined in claim 4, further characterized by aligned slits across the foundation body section, said slits defining an intermediate unsevered width, and a discous element of sheet material having a cut-out to define spaced segments engageable with the slits aforesaid, said element affording waist like support for the foundation while permitting flexure of the body section to and fro as well as laterally.

20 8. In a doll, manikin or lay figure, the combination of a combined head and body component of buckram with a felt backing, relatively detached arms and legs of like materials, a continuous basic reinforcement of sinuous wire medially bent to define complemental sections extending lengthwise from the top of the doll head

throughout the body and down the legs; similar wire reinforcing the arms and affording pivotal connection thereof relative to the head and body component; means securing said reinforcements to the respective foundation parts, composition counterpart halves applied to the head portion of the body component to give form thereto; and a felt covering enclosing and secured over the several parts aforesaid.

10 9. A doll, manikin or lay figure as defined in claim 8, wherein the arm reinforcing wire comprises a continuous length including a central deformed section of relatively longer bends for disposition crosswise at the back of the foundation with respect to the confronting part of the basic reinforcement.

15 10. A doll, manikin or lay figure as defined in claim 8, further characterized by composition feet, each one of said feet having a sinuous length of wire embedded therein, and means securing the projecting portion of said length of wire to the lower portion of the associated leg, whereby flexibility is afforded for movement of the feet.

20 11. A doll, manikin or lay figure as defined in claim 8, wherein the foundation head and body component is formed across the waist line with aligned inward and relatively spaced slits, and a discous sheet material reinforce having a cut-out, defining segments, engaging through said slots.

25 12. A doll, manikin or lay figure as defined in claim 8, wherein the composition head comprises face and back halves each of which has the ends of a strip embedded therein so as to define an anchorage loop, and adhesive strips are threaded through said loops to secure the respective head halves to the foundation and to one another.

30 MILDRED C. WOOD.
